UNITED STATES PATENT OFFICE.

FRANCIS H. RICHARDS, OF SPRINGFIELD, MASSACHUSETTS, ASSIGNOR TO THE AMERICAN BUTTON FASTENER COMPANY, OF NEW BRITAIN, CONNECTICUT.

BUTTON-SETTING MACHINE.

SPECIFICATION forming part of Letters Patent No. 369,260, dated August 30, 1887.

Application filed July 7, 1887. Serial No. 243,630. (No model.)

To all whom it may concern:

Be it known that I, FRANCIS H. RICHARDS, a citizen of the United States, residing at Springfield, in the county of Hampden and 5 State of Massachusetts, have invented certain new and useful Improvements in Button-Setting Machines, of which the following is a specification.

This invention relates to machinery for attaching shank-buttons to shoes or fabrics by means of malleable metallic fasteners.

The invention has for its object to furnish an improved machine of that class provided with an improved button-fastener magazine 15 and with button-feeding devices for presenting buttons to the fastener-setting mechanism.

For the attainment of this object the invention consists in certain improvements on the button-setting machine described in Letters Patent of the United States No. 311,033, granted to me January 20, 1885, and in the combinations hereinafter more fully set forth.

In the drawings accompanying and forming a part of this specification, Figure 1 is a front 25 elevation of a button-setting machine embodying my improvements. Fig. 2 is a side elevation of the same. Fig. 3 is an enlarged front view of a part of Fig. 1. Fig. 4 is an enlarged side view of a part of Fig. 2. Fig. 5 30 is a top view of the parts shown in Fig. 3. Fig. 6 is a vertical longitudinal section in line *a a*, Fig. 5. Fig. 7 is a horizontal section through the center of the feed-wheel and through the feed-strip guide. Fig. 8 is a side 35 elevation, partially in section and with some parts broken away, illustrating the construction and operation of certain parts of the mechanism. Fig. 9 shows in a different position some of the parts which are shown in Fig. 40. Figs. 10 and 11 are cross-sectional views in line *b b*, Fig. 9, and illustrate the operation of the movable stop, which, however, is shown unbroken. Fig. 12 is a side sectional view showing the magazine with its cover closed. In 45 Fig. 8 said cover is shown open. Fig. 13 is a cross-sectional view in line *c c*, Fig. 8. Fig. 14 is a cross-sectional view in line *d d*, Fig. 12. Fig. 14^a is a cross-sectional view in line *K K*, Fig. 8. Fig. 15 is a vertical section through

the presser-slide, and Fig. 16 is a rear elevation of the same. Fig. 17 is a top view of said slide drawn in projection with Fig. 16. Fig. 18 is a cross-sectional view in line *e e*, Fig. 15. Fig. 19 is a similar view in line *f f*, Fig. 15. Fig. 20 is a top view of the presser-slide cap, and Fig. 21 is a rear elevation of the same. Fig. 22 is a vertical section through said cap in line *h h*, Fig. 20. Figs. 23 and 24 are two views in projection of the movable stop and its operating stem and handle. Fig. 25 is a plan view of the under side of the setting-die.

Similar characters designate like parts in all the figures.

The frame of the machine, designated in a general way by *A*, consists or may consist of a hollow casting, substantially as shown, adapted to be supported on a column, *C*, or otherwise, and to carry the several parts of the respective mechanisms. Said frame has 65 bearings for a vertical presser-slide, *S*, for the magazine *M* and for the rock-shaft *R*. It is also constructed to rigidly hold the frame *H* of the button-feeding apparatus, which frame serves also as a head to carry the setting-die *B*.

The presser-slide *S* (best shown in Figs. 15 to 19) is grooved at 2 on its rear face to receive the driver *D*, which is supposed to be the same as the driver described in my aforesaid 80 patent. The upper end of said slide is formed to receive the cap *E*, whose back cross-bar, 44, forms the rearward wall of the driver-channel 4. Said slide *S* is also grooved at 3 on its front face to receive the stem 12 of movable 85 stop 5. (Shown in detail in Figs. 23 and 24.) The upper end of the slide is reduced, as at 60, Figs. 15, 17, to enter cap *E*, as in Figs. 8 and 9, and the point of set-screw 41 fits a corresponding countersink, 61, formed in the front 90 side of said reduced part, whereby the cap *E* is held in place against any rearward or downward pressure on bar 44. Said slide, which has its lower bearing on the stud *P*, fixed in the frame *A*, is held up by a spring, as 21, and 95 may be depressed by the driver *D*, provided the movable stop 5 is set in a proper position therefor, as shown in Fig. 10. The stud *P*

serves as a stop for the driver, it being adjustably secured in the frame A, (see Figs. 8 and 9,) for the purpose of adjusting the downward stroke of said driver.

5 The driver D is formed at its upper end to pass through the usual driver-channel, as 4, and may be operated by any suitable means, as the teeth of gear G, engaging with the teeth of rack V on the driver. Said driver is provided 10 at its lower extremity with means—as the horn 20, of suitable length and proportion—for engaging with the movable stop 5 when this is in its operative position. Power is or may be applied to the oscillating segment G through 15 a connecting-rod from an ordinary treadle mechanism, as described in my aforesaid patent, No. 311,033.

The movable stop 5 is provided with a stem, 12, and with a handle, 10, whereby it may be 20 swung from its working position in Fig. 10 to its non-working position in Fig. 11. This stop is used to enable the driver D in its downward movement to carry the presser-slide S down with it to release the fabric after the attachment thereto of a button. When in the 25 position shown in Fig. 11, said stop allows the driver D to travel to the lower end of its stroke without moving down the presser-slide.

The cap E (shown in detail in Figs. 20 to 22) 30 is held in position by a set-screw, 41, Figs. 8 and 9, the point 42 of which is let into slide S, thereby holding said cap securely on said slide and counteracting any tendency of the die-block B to press down the rear side, 44, of said 35 cap, and thus dislocate the same. This cap is thus removably secured for the purpose of permitting the convenient opening of the driver-channel in case any fasteners should become jammed in said channel.

40 The magazine M, usually made removable and held in place by set-screw 70, (shown in Figs. 2, 8, 12, 13, and 14,) consists or may consist of a cylindrical rod (either of integral or composite construction) longitudinally 45 grooved (see Fig. 14^a) to receive the T-shaped button-fasteners with their heads downward. This rod is ordinarily removably fixed in frame A. The magazine is provided with a cover, 6, pivoted at 13, follower 9, and spring 50 8. The cover 6 is provided with a groove, 14, to receive the prongs 15 of the fasteners 17. The sides of flanges 18 18 of said cover reach down to the heads 16 16 of the fasteners 17 to hold these in place while they are slid along 55 in the groove of the magazine. The fasteners shown in a body at 17 are thus held between the cover 6 and the lower wall, 19, of magazine-tube M. When the follower is drawn back, compressing spring 8, as shown in Fig. 8, the 60 cover 6 may be raised and secured in this position by allowing said follower to be held against it by spring 8, as shown in dotted position at 9". Having filled the magazine, the follower may be drawn back to the position 65 shown by full lines, Fig. 8, when the cover an be closed and the follower allowed to go forward, as shown in Fig. 12. The follower per-

forms the double function of driving the fasteners toward the setting mechanism and of locking the cover 6 in place when the same is 70 closed, and it is provided with a horn or projection, 21, which stands behind the fasteners in groove 14 in cover 6.

Fixed in or to the upper part of frame A there is a head or bracket, H, to the under 75 side of which the die-block B, Fig. 6, is attached in the usual manner. This die-block has formed therein the usual concave setting-die, 22, whose position is immediately over the driver-channel 4, and a button-shank-receiving cavity or socket, 72, into which the button-shank is entered by the button-feeding devices.

For presenting the buttons to the setting-die in proper position to be attached to the 85 fabric, I employ a revolving carrier or feed-wheel, F, which is similar to that described and claimed in United States Patent No. 319,507, granted to me June 9, 1885. This carrier consists or may consist of a disk provided with teeth 23 and a stem, 26, provided with a ratchet, 27. Said disk serves also as a stop-plate to prevent the buttons being pushed up too far by the fabric on the presser-slide during the operation of the machine. Upon 90 the face of carrier F are a series of button-holding springs, 25, corresponding in number with the button-receiving pockets or cavities in said feed-wheel. These springs may be separate or may be formed on or attached to 95 a disk, 24, turning on the same center as the carrier. These springs hold the shanks 29 of the buttons 45 into the shank-receiving cavity of the setting-die, as shown best in Fig. 6, and the button-head up against the lower edge of 100 the carrier. The feed-wheel is actuated by a pawl, 31, engaging with the teeth 35 of ratchet 27, which pawl is carried on an arm, 32, that is pivotally supported on stud 33, and is operated from rock-shaft R through some suitable connections. These connections may consist of an arm, 49, fixed on said rock-shaft, and the connecting-rod 38, connected to said arm 49 and arm 32. The buttons are fed to the 105 machine by means of a strip of some flexible material, as 36, through the perforations 37, in which the shanks of said buttons have been previously inserted. This feed-strip is guided to the feed-wheel through a channel, 39, which has suitable means, as flanges 40 40", for guiding said strip. The guard or cam-plate 34 is provided to lift the springs 25 and hold the same away from the buttons 28 until these shall have passed under said springs, after which the springs will pass off the plate, and bearing upon the buttons will hold these with 115 their shanks in groove 30 of the head H. The feed-wheel F being now rotated in the direction shown by the arrow, Fig. 3, the buttons 28 are carried by the teeth 23 of said wheel to a suitable position, as 45, to be attached to the fabric. At a suitable place, as 46, the strip 36 is deflected and guided away from the buttons 28 through a curved slot, thus re- 120 125 130

leasing the shanks 29 thereof. This operation is effected by means of the wedge 46, as best shown in Fig. 4. Previous to this, however, the buttons are brought under full control of 5 the revolving-carrier and the button-holding springs operating in conjunction therewith.

The operation of this improved machine is as follows: The parts of the machine being at rest, the driver D in about the position shown 10 in Fig. 9, the magazine M properly applied with fasteners, and the feed-wheel F with buttons, the fabric or other material, K, to which buttons are to be secured is placed in position on slide-cap E and under the setting-die, as shown in Fig. 4. The gear G being now started in the direction shown by the arrow 47, Fig. 8, the driver D is moved up, carrying the fastener into the upper end of the driver-channel 4. As soon as the driver D 15 starts from the position shown in Fig. 9, the presser-slide S is forced up against the fabric by spring 21, pressing said fabric against the die, as shown in Figs 2 and 4, and the fabric pressing the button-head up against the plate 20 F, which serves (besides being a carrier) the purpose of a stop for said heads. The continual upward movement of the driver then forces the fastener-prong through said fabric, through the shank of the button 45, and against 25 the setting-die, and thereby sets the fasteners, all in the usual manner. The motion of the gear G being now reversed, the driver D is carried downward, and at the latter part of its movement returns the presser-slide S to the 30 position shown in Fig. 9. The feed-wheel F is moved forward one division, carrying the attached button 45 away from the setting-die and presenting another button ready to be attached to said material, K. All the parts are 35 now returned to their original positions ready for a repetition of the entire operation.

It is generally desirable that the presser-slide should be lowered before the button-shank comes to the setting-die. For this purpose the stop 5 is ordinarily used in its working position, as shown in Figs. 9 and 10; also, the movement of pawl 31 may be somewhat in excess of the exact amount required to turn the ratchet 27 through the space of one tooth. 40 In this way the movement of the carrier may be delayed in relation to the other movements of the machine for the purpose of lowering the slide more promptly away from the button which is being placed ready for setting.

50 It will be understood that this apparatus is capable of modification in various ways and degrees after the manner of machines in general within the scope and limits of my invention.

55 Having thus described my invention, I claim—

1. The combination, in a button-setting machine, of a setting-die, a presser-slide having a vertical movement under said die, being 60 normally upheld by a spring, and having a driver-channel, a driver working in said channel, a lever operatively connected to actuate

70 said driver and through said driver to move down said slide, a rotary carrier for feeding buttons to position for setting above said channel, and connecting mechanism, substantially as described, between said lever and carrier, the whole being timed and coacting to first move up together the driver and presser-slide, then complete the upward stroke of the driver, 75 next lower the driver and presser-slide, and complete together the downward stroke of said slide and the forward movement of the carrier, substantially as described.

2. The combination, in a button-setting machine, of the setting-die having a cavity for receiving the button shank or eye, a revolving stop-plate in front of said die, limiting the upward movement of the button-head, and the button-holding spring 25, fixed on said 80 plate and operating to hold the button with its head against said plate and with its shank in said cavity, substantially as described.

3. The combination, in a button-setting machine, of the carrier or feed-wheel, a frame 90 supporting the carrier and having a passage for the button-strip, and the incline arranged and operating to withdraw the said strip from the button-shanks after the button-heads are engaged by said carrier, substantially as set 95 forth.

4. The combination, in a button-setting machine, with a fixed frame having a groove for the button-shanks, of the rotary carrier engaging the buttons and operating to slide the 100 same in said groove, and button-holding springs moving with said carrier and bearing on the button-heads, substantially as described.

5. The combination of the toothed carrier, 105 the button-holding springs moving with said carrier, and the guard lifting said springs to admit the buttons thereunder, substantially as described.

6. The combination, in a button-setting machine, of a frame, as H, provided with a die, 110 and bored to receive the hub of a revolving button-carrier, the carrier F, provided with a hub, 26, having its bearing in said bore and having ratchet-teeth, lever 32, having a pawl acting on said teeth, and a screw or stud, 33, 115 passing through said carrier hub and lever, all substantially as set forth.

7. The combination, with the grooved presser-slide, of the cap E, inclosing the upper end of said slide, and having means (as a set-screw or the like) for clamping the same against the grooved side of said slide, substantially as set forth.

8. The combination, in a machine of the class described, of the presser-slide, the driver 125 sliding thereon, and a movable stop, substantially as described, carried on said slide, and arranged to be moved under and from under the driver, substantially as set forth, and for the purpose specified.

9. The combination, in a machine of the class described, of the slide S, the driver, and the swinging stop 5, carried on said slide, said stop having a stem furnished with a handle 130

for operating the same, all substantially as set forth.

10. The combination, in a button-setting machine, of the magazine M, the cover 6, and the 5 follower 9, all arranged and operating substantially as set forth.

11. The combination, in a button-setting machine, of the magazine, the magazine-cover, the follower, and the spring 8, all arranged 10 and operating substantially as set forth.

12. The combination, in the button-feeding mechanism of a machine, of a guide for the button-strip and a rotary toothed carrier operating to feed said strip by the engagement of the carrier-teeth with the buttons on said strip, 15 all substantially as described.

FRANCIS H. RICHARDS.
